UNITED STATES PATENT OFFICE

2,489,609

THREAD-FEEDING MECHANISM

Roy C. Amidon, Reading, Pa., assignor to Vanity
Fair Mills, Inc., a corporation of Pennsylvania

Application February 17, 1947, Serial No. 729,102

10 Claims. (Cl. 66—86)

1

The invention particularly relates to the mechanism for feeding or delivering thread from warp beam spools, bobbins, etc. of knitting machines to the needles during the knitting process. In the production of fabrics made upon tricot or so-called fast warp machines, or in any process of using the warp principle, the density of the fabric or tightness of the stitches is largely determined by the feeding (portion of thread or yarn allotted to each knitting cycle). In order to prevent the formation of so-called stop marks frequently found in fabrics when the beam let-off is uneven or irregular it has been found desirable to provide some means of effecting a continuous rotation of the beam in a manner to let-off exactly the amount of thread or yarn that is required by the needles.

In knitting machines in which the let-off of the yarn is effected by the pull of the needles for starting the rotation of the beam, the movement of the beam is not continuous but is intermittent and brake devices have heretofore been provided to operate on the beam and prevent its overrunning.

Various methods have been proposed, with more or less success, to drive the beam through suitable speed adjusting devices so as to deliver the thread or yarn at a fixed linear speed. All such devices heretofore devised and have come to my knowledge are open to more or less objection as, for instance, they are too complicated or too expensive, or both.

My present invention, therefore, has for its object to provide a simple, inexpensive and effective mechanism for directly driving the beam regardless of the varying diameter of the thread or yarn so as to let-off the thread or yarn at a predetermined linear speed directly related to the rate of thread being used by the needles in the knitting process. This I accomplish by driving two rollers in contact with the thread on the beam and at a constant speed and so mounting the rollers as to exert a pincers action on the beam, thereby maintaining uniform and constant (non-slipping) contact between the rollers and the thread on the beam at all times, and thereby feeding off the thread or yarn from the beam at a uniform linear speed regardless of the decreasing diameter of the beam from maximum to minimum.

To the attainment of the aforesaid objects and ends the invention further resides in those novel details of construction, combination and arrangement of parts, all of which shall first be fully described hereinafter and then be specifically

2

pointed out in the appended claims, reference being had to the accompanying drawings in which:

Fig. 1 is an elevation of a portion of a knitting machine illustrating my invention.

Fig. 2 is a side elevation of the same looking from left to right in Fig. 1.

Fig. 3 is a diagrammatic view of a modification wherein only one roller contacts the thread on the beam.

Fig. 4 is a diagrammatic view of a modification in which a speed changer is employed between the main or cam shaft of a machine and the beam driving means.

In the drawings in which like numerals and letters of reference indicate like parts in all the figures, 1 represents a portion of the frame of a knitting machine which carries the bearings 2 for the shaft 3 of a beam 4.

20 Mounted in suitable bearings 10 on frame 1 is a driven shaft 5 on which is a sprocket 6 driven by a chain 8 from sprocket 7 on a shaft 9. The shaft 9 may be the first motion shaft, the cam shaft or any other suitably located shaft of the machine which rotates at a constant continuous speed in harmony with the operations of the needles.

25 Freely pivoted on the shaft 5 are pairs of arms 11 and 12. At least one sprocket 13 is secured to shaft 5. One pair of arms 11 carries a roller shaft 14 on which is a beam-thread-contacting and turning roller 21 while a similar shaft 14 and roller 21 are carried by the other pair of arms 12.

30 At least one sprocket 15 is secured to each shaft 14 over which sprockets 15 and 13 and over a spring-loaded idler sprocket 18 a chain 16 passes, by virtue of which when shaft 5 is turned shafts 14, 14 will likewise be turned.

35 The arms 11 and 12 are so positioned that their rollers 14 will engage the thread on the beam at opposite sides of a plane containing the axes of shafts 3 and 5 (see Fig. 2). The lengths of arms 11 and 12 should preferably be the same, and not longer than the distance from shaft 3 to shaft 5, so that a straight line drawn from one shaft to the other will lie between shafts 3 and 5.

40 The sprocket 18 has its shaft 17 journalled in a block 19 mounted to slide in a slideway 24 located between the axes of shafts 3 and 5, a spring 20 serving to press the block in a direction to keep the chain 16 taut and also to press the rollers 14 in contact with the thread on the beam 4 in directions to exert somewhat of a

pincers action and thereby tend to force the beam in a direction to maintain it in its bearing against riding out of the same.

If desired, a change-speed mechanism 22 of suitable character may be introduced between shaft 9^b and shaft 5^b (see Fig. 4). By suitably adjusting the mechanism 22, the thread or yarn may be fed to the needles at predetermined increased or decreased speeds to produce a variety of different patterns and effects. Such a speed-changing or adjusting mechanism is well known in the art and need not be specifically described herein but see Fig. 3 of the Bassist Patent No. 2,303,903, issued December 1, 1942.

Those parts in Fig. 4 corresponding to like parts in the preceding figures bear the same reference numeral plus the index letter *b* and need not be further described.

In Fig. 3 I have shown a single arm drive for the beam. In this figure those parts which are the same as corresponding parts in the preceding figures bear the same reference numerals plus the index letter *a* and need not be further described here. When the single arm (or pair of arms) is used a suitable tensioning device similar to that shown in the preceding figures may be used to tension the chain 16^a and keep roller 21^a against the beam 4^a.

While I have illustrated the single arm and roller embodiment of my invention (Fig. 3) I prefer the embodiment of Figs. 1 and 2 as being more practical and accurate in operation than where a single contact roller is employed.

The rollers 21, 21^a are of sufficient length to function properly but they need not and preferably do not extend over the full length of the beam.

It will be seen that the rollers 21 and their drive mechanism do not interfere with the travel of the thread from the beam to the needles.

While my invention has been devised principally for use on knitting machines, it can also be adapted to other uses as well, for example, weaving machines.

Since the shaft 5 is driven at a constant speed the rollers 21 will likewise be turned at a constant speed and as they are held in pressure contact with the thread on the beam they will turn the beam so that the thread leaves the beam at the same linear speed all the time the machine is in operation or until all the thread has been let-off the beam. As the thread is rolled off and the diameter of the thread on the beam progressively lessens, the speed at which the beam turns will correspondingly be increased all without the use of cumbersome brake or lever operated beam controls such as have heretofore been proposed.

From the foregoing description taken in connection with the accompanying drawings it is thought that the construction, operation and advantages will be clear to those skilled in the art.

What I claim is:

1. In a thread-feeding mechanism, means for letting-off the thread from a beam continuously at a predetermined linear speed, said means including a power driven shaft, at least one arm pivoted on said shaft, a beam-thread-engaging and turning roller carried by said arm, means continuously acting to maintain said roller at all times in operative contact with the thread on the beam, and means operatively connecting said roller with said driven shaft to turn said roller at a predetermined speed.

2. In a thread-feeding mechanism wherein thread is fed from a rotatable beam or the like mounted to turn in suitable bearings, the improvement which includes a suitably mounted driven shaft, two arms pivotally mounted at one end and each carrying at its other end a beam-thread-engaging and driving roller, said arms being disposed so that the respective beam-thread-engaging and driving rollers engage the thread on the beam at opposite sides of a plane containing the beam axis and the arm pivot axis, said rollers having shafts, a driving connection between said driven shaft and said roller shafts to turn said rollers at the same speed, and means causing said rollers to maintain rolling contact with the beam at all times.

3. In a thread-feeding mechanism wherein thread is let-off from a body on which it is wound, the improvement which comprises a supporting frame having U-shaped bearings in which said body is mounted to turn about its axis, means including a pivoted arm which carries a body-thread-engaging roller simultaneously engaging the thread, turning said body and forcing said body in a direction to hold it down in its bearings.

4. In a thread-feeding mechanism wherein thread is let-off a cylindrical body on which it is wound, said body having a shaft, the improvement which comprises a suitable frame having suitable bearings for said shaft to turn in, two pairs of arms pivotally mounted in said frame, rollers having shafts, one journaled in each pair of arms and disposed to engage the winding on said cylindrical body at opposite sides of a radius of said body, means continuously urging said rollers into rolling contact with said winding and means for turning said rollers at the same constant speed to let-off the thread at a predetermined linear speed regardless of the changing diameter of the wound body.

5. A mechanism according to claim 1 wherein a speed adjusting mechanism for said driven shaft is provided.

6. A mechanism according to claim 4 wherein the arms are pivoted on a common axis.

7. In a mechanism of the class described wherein is provided a supporting frame having bearings, a beam rotatably mounted in said bearings, and a first motion shaft journaled in bearings in said frame, the invention which comprises a driven shaft also journaled in bearings in said frame, a suitable driving connection between said shafts, two roller carriers pivoted each on said driven shaft, beam-thread-engaging and turning rollers carried one on each roller carrier for engaging the thread on the beam at opposite sides of a plane containing the axis of said beam and the axis of said driven shaft, an endless driving connection between said driven shaft and each of said rollers for turning said rollers both at the same speed, and means continuously urging said rollers toward said beam and maintaining the rollers in rolling contact with the thread on the beam.

8. A mechanism according to claim 7 wherein the last named means includes said endless driving connection and a spring-pressed roller over which said driving connection passes and by which said driving connection is kept taut.

9. A mechanism according to claim 7 wherein the length of said arms is not in excess of the distance between the axis of said driven shaft and the axis of the beam, by virtue of which the pressure of said rollers against the thread on the

beam results in a force tending to hold the beam down in its bearings.

10. In a thread-feeding mechanism wherein thread is fed from a rotatable beam or the like mounted to turn in suitable bearings, the improvement which includes a suitably mounted driven shaft, two arms pivotally mounted at one end and each carrying at its other end a beam-thread-engaging and driving roller, said arms being disposed so that the respective beam-thread-engaging and driving rollers engage the thread at opposite sides of a plane containing the beam axis and the arm pivot axis, said rollers having shafts, means for driving said shafts at the same speed from said driven shaft to turn said rollers 15 at the same speed, and continuously acting means

for drawing said arms toward one another to maintain said rollers in contact with the beam during the operation of the machine.

5 ROY C. AMIDON.
